UNITED STATES PATENT OFFICE.

JOSEPH H. CAMPBELL, OF NEW YORK, N. Y., ASSIGNOR OF THREE-EIGHTHS
TO CHARLES H. CAMPBELL AND JAMES McLAIN, BOTH OF SAME PLACE.

METHOD OF UTILIZING AQUA-AMMONIA AS A MOTIVE POWER IN ENGINES.

SPECIFICATION forming part of Letters Patent No. 337,372, dated March 9, 1886.

Application filed July 27, 1885. Serial No. 172,776. (No model.)

To all whom it may concern:

Be it known that I, JOSEPH H. CAMPBELL, a citizen of the United States, residing at New York, in the county of New York and State 5 of New York, have invented certain new and useful Improvements in Methods of Utilizing Aqua-Ammonia as a Motive Power in Engines, of which the following is a specification, reference being had therein to the accompanying 10 drawing.

My invention relates to improvements in the method of utilizing aqua-ammonia as a motor-power in engines.

My invention consists in the method here- 15 inafter described of introducing the vapor generated in the boiler into the storage-reservoir below the surface of the liquid in said reservoir, thereby securing the absorption of the vapor and the heat developed by the absorp- 20 tion to superheat the vapor in the reservoir.

My invention consists, further, in regulat- 25 ing the tension of the vapor in both boiler and reservoir by the introduction of the binary liquid into either, as the pressure may re- quire.

My invention consists, further, in the meth- 30 od of heating the cylinder, so as to superheat the working-vapor therein, by means of the exhaust-vapor from the cylinder, combined with a cool weak solution of aqua-ammonia under pressure, which absorbs the vapor, and thereby increases the temperature of the cylinder when brought into a chamber which surrounds the cylinder.

My invention consists, further, in the meth- 35 od of drawing off from the chamber which surrounds the cylinder the vapor which is in ex- cess of saturation, and thus preventing back- pressure.

My invention consists, further, in the meth- 40 od hereinafter described of disseminating the heat of absorption by the neutralizing effect of the expanded vapor within the cylinder of the engine.

For the purpose of illustrating my inven- 45 tion, I have shown in the drawing a longitudinal view, partly in section, of the boiler, reservoir, cylinder, cooler, absorber, pump, and valves which constitute my machine or 50 plant, and such will be described hereinafter in detail.

A indicates the boiler, which may be of any suitable or desirable construction, and is connected to and communicates with the reservoir B by means of the pipe C, said pipe be- 55 ing provided with a plug-valve, *a*, and is de- signed to transfer the aqua-ammonia from the boiler to the reservoir, or vice versa, accord- ing to the required pressure or tension.

B is the dynamical reservoir and superheat- 60 er, the upper portion of said chamber being the superheater and the lower portion the dy- namical reservoir.

D is a pipe leading from the upper portion 65 or vapor-space of the boiler to the reservoir B, said pipe entering through the bottom of the reservoir and extending up into the same, where it is bent into a return-curve, so as to discharge the vapor below the surface of the liquid contained in the reservoir. The pipe 70 D is provided with a check-valve, *e*, to pre- vent the liquid in the reservoir from being forced back into the boiler, where the pressure in the reservoir is in excess of that in the boiler. This valve *e* opens upward, so as to 75 allow the free passage of the vapor from the boiler to the reservoir.

The object of discharging the expelled va- 80 por into the reservoir below the surface of the liquid is to comply with the conditions of ab- sorption—viz., bringing the liquid and vapor into contact. If the vapor were discharged above the surface of the liquid in the reser- 85 voir, since water will not transmit the radiant heat of steam, and the diathermancy of am- moniacal vapor is only 1.1195, (air being 1,) a non- diathermic diaphragm is formed by the heated 90 surface of the liquid, which not only prevents the heat from passing down into the reservoir, but also acts as a barrier to prevent the re- solution of the expelled vapor with the liquid in the reservoir; consequently the heat of ab- sorption is not generated to superheat the va- 95 por in the reservoir. The boiler A is also connected to the reservoir by the pipe E, which extends up into the vapor-space of the reser- 100 voir and returns by a series of coils, *d*, down to or near the water-line, and then straight through the liquid and bottom of the reser- voir B.

The object of coiling the pipe E in the va- por-space of the reservoir is to increase its

heating-surface to superheat the vapor, so that the tension of the vapor therein contained can be raised to the proper working-pressure without materially changing the temperature of the fluid in the reservoir; and, furthermore, the liquid in its passage through the coil gives off a certain amount of its heat to the liquid and vapor in the reservoir, thereby becoming partially cool before entering the cooler F.

10 The pipe E, after passing through the bottom of the reservoir B, is coiled, as shown at e, said coil being inclosed in a chamber, F, which is supplied with cold water by means of the pipe f. The object of thus cooling the weak 15 solution of aqua-ammonia which passes through this pipe is to restore its absorptive power before it is brought into contact with the exhaust-vapor.

10 The pipe E is provided with a valve, G, of 20 the well-known type of safety-valves, the head of said valve being provided with an elbow-lever, H, having a weight, I, on its horizontal arm, said weight being adapted to be adjusted on said arm, so as to hold the valve open 25 and allow the free passage of the hot liquid from the boiler to the coil of the pipe E in the reservoir B.

10 The vertical arm of the lever passes up into 30 a stuffing-box, K, which is connected to the reservoir B by a pipe, L, so that when the pressure in the reservoir rises above the desired point it causes the valve G to close and shut off the flow of the hot liquid from the boiler A to the reservoir B through that portion 35 of the pipe E until the vapor pressure in the latter is reduced to the proper working-point.

10 In order to maintain under boiler-pressure 40 a constant supply of the cooled weak solution sufficient to absorb the exhaust-vapor from the engine, a pipe, M, is connected to that part of the pipe E which is between the safety-valve and the boiler, so that when the valve G closes and cuts off the supply of hot liquid 45 through the pipe and coil within the reservoir the valve g may be opened and the liquid allowed to flow uninterruptedly from the boiler through the coil e into the cooler F by way of the pipe M.

10 N is a pipe provided with a throttle-valve, h, which connects the reservoir B with the cylinder O, through which pipe the proper amount of vapor is admitted to work the piston of the cylinder, the exhaust-vapor from 55 the cylinder being carried up through the pipe P, where it meets with the cooled weak solution from the boiler, as will now be described.

10 The pipe E, after leaving the cooler F, extends upward some considerable distance 60 above the cylinder, where, by means of a T-joint, it is connected to the pipe Q in a nozzle or contracted portion, i. The pipe P is also connected to the upper end of the pipe Q by means of the elbow-joint k, so that the exhaust-vapor 65 from the cylinder is brought into contact with the cold weak solution from the pipe E, which absorbs the vapor, and is conducted to the

jacketed space R of the cylinder, and by which means the cylinder is kept at the proper working-temperature wholly by the heat of absorption. If the cylinder is not thus protected, on account of the low boiling-point of ammonia and the comparatively high temperature of the working-vapor, a very wide range of temperatures is possible. The great depression 70 of temperature within the cylinder, consequent upon the expansion of the vapor, would cool the body of the cylinder to such an extent that a great portion of the heat carried into the cylinder by the vapor would be required to 75 restore the cylinder to the proper working-temperature. It has been found in practice that the vapor entering the cylinder at 195° temperature and let down through the cylinder by expansion is exhausted at 40°, which 80 depression would be further increased by an earlier cut-off within the cylinder. By the above process the body of the cylinder can always be maintained at a temperature of 150°, however low the temperature of the exhaust 85 may be.

10 I will remark in this connection that the cold weak solution is sprayed into the upper end of the pipe Q under boiler-pressure, and carries with it the exhaust-vapor from the 95 pipe P, said vapor being readily absorbed in the liquid, by reason of its reduced temperature, and by reason of its being sprayed or forced into mechanical union with the vapor by the pressure from the boiler.

10 S is a pipe of smaller diameter than the pipe E, and communicates therewith by means of the T-joint, the lower end of said pipe S being connected to a pipe, T, leading to the absorber V.

10 W is a pipe leading from the jacketed space of the cylinder to the absorber V, through which the liquid is passed to the absorber after having done its work in heating the cylinder.

10 As before stated, the exhaust-vapor from the cylinder which has passed up through the pipe P and been mingled with the cold weak solution coming over from the boiler through the pipe E is forced down under pressure into 115 the jacketed space of the cylinder, where it gives off its heat to keep the cylinder at the proper working-temperature. This, as a natural consequence, after working for some time, raises the temperature in the jacketed space 120 to such an extent as to revaporize a portion of the absorbed vapor, and in order to prevent the back-pressure of the vapor thus revaporized from interfering with the proper working of the piston I connect the jacketed space of the cylinder with the pipe S, leading to the absorber, by means of the pipe A'. This arrangement enables the vapor formed in the jacketed space to pass out and be brought into contact with the cooled weak solution in 130 the pipe S when the vapor is absorbed, and passes down into the absorbing-chamber V. In case a greater amount of cold solution than can pass through the pipe S is required to

absorb the vapor from the cylinder, I connect the pipe E with the pipe T by means of the pipe B'. This enables me to bring the requisite amount of cold solution into contact with the vapor from the jacketed space to effect a complete absorption of the vapor. The absorber V is supplied with the requisite amount of water to cool the liquid by means of the pipe f, which also supplies the cooler F. The solution, after leaving the absorber V, is forced back into the boiler A or reservoir B, through the pipes C' D', by means of the pump E', the pipes C' and D' being provided with valves a' b', respectively, which enables the operator to admit the solution into either the boiler or the reservoir. This is an important feature in my invention, as it enables the operator to increase or decrease the tension in both boiler and reservoir as occasion may require.

It will be noticed that the vapor enters the cylinder at a temperature of 230°, having a corresponding pressure of sixty pounds to the square inch, is cut off at an early point in the stroke, as is the case in working steam expansively, and is expanded down through the remaining portion of the stroke. On account of the high pressure at this low temperature, 230°, the vapor will be exhausted at an exceedingly low temperature. To prevent the body of the cylinder from having the same temperature, the exhaust-vapor and the weak cooled solution are united in the jacket of the cylinder. While the heat generated by this union tends to maintain the cylinder at a high temperature, the heat is thus disseminated that would otherwise be carried over to the absorber and to this extent assists, or is auxiliary to the absorber.

Having thus described my invention, what I claim, and desire to secure by Letters Patent, is—

1. In a vapor-engine, the method herein described of securing the absorption of the vapor and the heat developed by the absorption to superheat the vapor in the reservoir,

the same consisting in introducing the vapor generated in the boiler into the storage-reservoir below the surface of the liquid contained in said reservoir.

2. In a vapor-engine, the method herein described of regulating the tension of vapor in both the boiler and reservoir, the same consisting in introducing the binary liquid into either under pressure from the pump, as set forth.

3. In a vapor-engine, the method herein described of heating the cylinder of the engine so as to superheat the working-vapor therein, the same consisting in combining the exhaust-vapor from the cylinder with a cool weak solution of aqua-ammonia under pressure in a chamber which surrounds the cylinder, as set forth.

4. In a vapor-engine, the method herein described of preventing back-pressure on the piston of the engine, the same consisting in drawing from the chamber which surrounds the cylinder the vapor which is in excess of saturation by means of a stream or current of the cool weak solution under pressure from the boiler, as set forth.

5. A vapor-engine in which the vapor is worked expansively in the cylinder, the method herein described of disseminating the heat of absorption produced by the union of the cold weak solution and the exhaust-vapor within the jacket of the cylinder, the same consisting in joining or combining the exhaust-vapor from the cylinder with a weak solution under boiler-pressure in the jacket of the cylinder, thus neutralizing the effect of the expanded vapor within the cylinder, and the consequent fall of temperature resulting from such expansion.

In testimony whereof I affix my signature in presence of two witnesses.

JOSEPH H. CAMPBELL.
